Continuation of application Serial No. 358,606,
September 27, 1940. This application November
12, 1947, Serial No. 785,230

14 Claims. (Cl. 260—668)

1

The present invention pertains to the manufacture of toluene in a substantially pure state, and more particularly, to the isolation of pure toluene from mixtures thereof with other hydrocarbons. This application is a continuation of my prior application Serial No. 358,606, filed September 27, 1940, now abandoned.

For various purposes, toluene may be satisfactorily utilized only in substantially pure condition. The "nitration grade" of toluene, for example, used in the manufacture of explosives in this country, consists of about 99.9% toluene. Heretofore, the by-product coke industry has been the principal source of toluene, and since it is merely a by-product in that industry the quantity available is necessarily limited. Toluene occurs to a minor extent in various petroleum fractions and products, and various proposals have been advanced for the recovery of toluene from such materials by known physical methods of separation such as extensive fractional distillation, solvent extraction, and the like. While the separation of pure toluene is theoretically possible by these methods, from a practical economic standpoint except in rare instances they are far from satisfactory and for the most part are of only academic interest because of the complexity and cost of the separation.

One of the primary objects of my invention is the provision of a process whereby these disadvantages are obviated, and substantially pure toluene may be readily and economically produced from straight chain or aliphatic hydrocarbons commonly occurring in petroleum fractions.

A further object of my invention is the provision of a process whereby pure toluene may be produced from petroleum naphtha or similar hydrocarbon mixtures in conjunction with the production of motor fuel of high antiknock quality, and the gaseous and liquid products produced in the manufacture of the fuel may be most effectively utilized in the production of pure toluene.

A further object of my invention is the provision of a process capable of general application in the production of pure toluene from toluene-rich hydrocarbon mixtures containing, in addition to toluene, non-aromatic hydrocarbons having boiling points differing only slightly from the boiling point of toluene.

Pursuant to a preferred mode of practicing the invention, a highly aromatic mixture including a substantial quantity of toluene is first produced by the dehydrogenation and cyclization

2

of aliphatic and naphthenic compounds having 6 or more carbon atoms in the carbon chain over a suitable catalyst. For this purpose petroleum naphthas constitute a suitable feed stock, and I greatly prefer to carry out the initial stage of the process by contacting the naphtha at an elevated temperature with a suitable dehydrogenating and cyclizing catalyst in the presence of added hydrogen and under less severe or drastic conditions of treatment than those obtaining in a second catalytic conversion step employed in the process. The highly aromatic product produced in the first stage may then be separated into an intermediate fraction rich in toluene, and higher and lower boiling fractions which may be blended to produce a motor fuel of exceptionally high antiknock quality. The toluene-rich fraction is thereafter contacted in a second stage with a dehydrogenating and cyclizing catalyst, preferably under more drastic conditions and in the presence of hydrogen produced in the first stage to convert non-aromatic constituents present in this fraction to aromatic hydrocarbons having boiling points relatively widely separated from that of toluene. From the resulting mixture substantially pure toluene may be readily separated by fractional distillation, solvent extraction or other conventional methods of separation.

The various features, advantages, and mode of operation of my invention will be evident from the following detailed description of one embodiment thereof given in connection with the appended drawing.

The appended drawing illustrates a suitable arrangement of apparatus, and process flow, for the manufacture of pure toluene from petroleum naphtha pursuant to my invention.

A suitable feed stock, for example a virgin naphtha, containing a large amount of aliphatic hydrocarbons containing 6 to 12 carbon atoms, is introduced through line 1, by pump 2, into a heating coil 3 in furnace 4. A suitable amount of a hydrogen-containing gas, preferably a recycle gas derived from the conversion products produced in reactor 7, is introduced through line 5 and added to the naphtha feed in line 1 and passed through the heating coil 3 therewith. Optionally, the hydrogen-containing gas may be heated in a separate coil and mixed with the hydrogen at a point immediately preceding catalyst tower 7 or the hydrogen may be introduced into catalyst tower 7 at suitably spaced intervals throughout its length. After being va-

porized and heated to a suitable temperature in coil 3, the mixture of naphtha and H₂ is passed by line 6 into catalyst tower 7.

Catalyst tower 7 is filled with a suitable dehydrogenating and cyclizing catalyst, for example, molybdenum oxide supported on activated alumina. The mixture of naphtha and added hydrogen is passed through tower 7 in contact with the catalyst at a feed rate and under other reaction conditions adapted to convert the aliphatic compounds present in the naphtha to aromatic compounds, such as benzene, toluene, and xylene, together with a certain amount of olefinic hydrocarbons, and various other hydrocarbons resulting from the limited amount of thermal decomposition which takes place. Tower 7 is preferably maintained under a suitable degree of superatmospheric pressure. The particular operating conditions employed in this stage of the process, charging stock, and catalyst, may suitably correspond to those disclosed and claimed in co-pending application Serial No. 294,784, filed September 13, 1939, now Patent No. 2,320,147 issued May 25, 1943, the latter application being directed primarily to the production of a highly aromatic naphtha especially suitable for use as a high quality antiknock motor fuel. Thus, for example, the following conditions may be employed: a temperature between about 875° F. and about 1075° F., a total pressure of the order of 50 to 450 pounds per square inch, a mol ratio of hydrogen to naphtha charged between about 0.5 and about 8 and a space velocity of 0.05 to 5.0 volumes of liquid hydrocarbons charged per volume of catalyst space per hour.

From tower 7 the conversion products are withdrawn through line 8 and pass through a condenser 9 and then into a high pressure separator 10. The pressure within separator 10 is suitably controlled by valve 13 to separate the total conversion products into normally gaseous constituents, including hydrogen and gaseous hydrocarbons containing 1 to 3 carbon atoms and into normally liquid constituents, the gaseous fraction being withdrawn overhead through line 11 and the liquid product from the bottom of the separator through line 12.

A portion of the hydrogen-containing gas withdrawn through line 11 is added to the naphtha feed to tower 7, by recirculating it by compressor 14 through line 5, the quantity thus circulated being regulated by valve 15. Operating conditions suitably maintained in the first stage of the catalytic treatment in catalyst tower 7, are illustrated by the following example of the conversion of a 44 octane number naphtha having an initial boiling point of 240° F., an end point of 418° F., and an A. P. I. gravity of 51.4°, over a molybdenum oxide-alumina catalyst wherein the following conditions were maintained in the catalyst tower 7:

Example

Temperature, inlet of reactor ..... °F. 1015
 Temperature, outlet of reactor ..... °F. 925
 Pressure ..... lbs./sq. in. 300
 Feed rate

      vols. naphtha/hr./vol. of catalyst 0.75

Hydrogen gas recycle

      cu. ft./bbl. of naphtha 2600

Length of on-stream period ..... hrs. 6

From this operation there was obtained a highly aromatic gasoline having an octane number of 80 C. F. R. M., and containing approximately 7.5% by volume of toluene.

The gaseous fraction withdrawn overhead through line 11 contained a relatively large amount of hydrogen, amounting to about 60%, the remaining constituents being normally gaseous hydrocarbons containing 1 to 3 carbon atoms. In addition to gaseous and liquid products, a small amount of carbonaceous material was deposited on the catalyst amounting to 0.6% by weight of the charge.

10 The deactivating deposit of carbonaceous material on the catalyst was removed after the on-stream period by an oxygen-containing gas supplied through line 39 and withdrawn through line 40, by the method conventional in the art. 15 It is also to be understood that while only one reactor 7 has been shown, a plurality of such reactors is usually employed manifolded in a parallel relationship so that one reactor is on-stream, while the other is undergoing regeneration, thereby attaining continuous operation. A 20 similar arrangement of multiple reactors and regeneration means, lines 47 and 48, for introducing and withdrawing an oxygen-containing gas are likewise used with respect to the second catalytic reactor 26.

25 The hydrogen-containing stream of gas from line 11 is preferably split, a portion being utilized for recycling through line 5, and another portion is forwarded through line 27 for use in the second catalytic stage, the net hydrogen produced being withdrawn through line 41.

30 The operating conditions maintained in reactor 7, indicated by the foregoing example are preferably of substantially less severity than those 35 maintained in the second stage of catalytic treatment effected in catalyst tower 26. The maintenance of this difference in relative severity has been found to be highly advantageous since a high yield of toluene, as well as a hydrogen-containing gas of relatively high hydrogen concentration, are thus produced in the first stage of the process, and both of these factors are important in the securing of the best results in the second catalytic stage.

35 The liquid product withdrawn through line 12, or a portion thereof, is passed by line 27 to a suitable fractionator 16 wherein a close boiling toluene-rich cut containing as large a proportion of toluene as may be satisfactorily separated is 40 withdrawn as a side stream through line 17 and passed to a side stream stripper 18. A suitable stripping medium such as steam is supplied to the bottom of the side stream stripper through line 19 to further increase the concentration of toluene by removal of lighter boiling components, 45 these components and stripping medium being withdrawn overhead from the stripper through line 20 and returned to the upper portion of the fractionator. The overhead product from fractionator 16 is withdrawn through line 42, condensed in condenser 43, and sent to gasoline storage through line 44. The bottom fraction withdrawn through line 45, together with any portion of the total liquid withdrawn by line 46 50 from separator 10 not required for the production of toluene, is likewise sent to gasoline storage through line 44.

55 A fraction relatively rich in toluene is thus produced and withdrawn from the bottom of side stripper 18 through line 21. In addition to toluene, this fraction contains non-aromatic hydrocarbons which are extremely difficult to separate from the toluene to the extent required for the production of substantially pure toluene by 60 any commercially available methods such as frac-

tionation, solvent extractions, etc. Normally, the toluene-rich fraction may be and is preferably produced with toluene concentrations in excess of 50% and in most instances concentrations of the order of about 75% or greater may be obtained with conventional types of fractionating equipment. The non-aromatic constituents of the toluene-rich fractions will usually include paraffins, olefins, and naphthenes, and consist largely of compounds containing 6 to 8 carbon atoms in the carbon chain, the eight carbon compounds usually constituting a predominating proportion of the non-aromatic fraction.

The toluene-rich fraction is introduced by pump 22 into heating coil 23 in furnace 24 wherein it is vaporized and heated to a temperature suitable for the catalytic conversion effected in catalyst tower 26. A relatively highly concentrated hydrogen-containing gas, preferably a fraction of that produced in the first stage, is admixed with the toluene fraction through line 27'. This hydrogen, similar to the hydrogen introduced through line 5, may be heated in the same coil with the toluene-rich fraction as shown, or heated separately and introduced at a point in line 25 intermediate the heater and catalyst tower or into the catalyst tower 26 at a plurality of spaced points throughout the length of the tower. The toluene-rich fraction and hydrogen as shown are introduced into catalyst tower 26 through line 25 and pass therethrough in contact with the catalyst.

Operating conditions suitably maintained in reactor 26 are indicated by the following example of the conditions obtaining in the treatment of a fraction containing 75% toluene and the remaining 25% consisting of hydrocarbons boiling within the range of about 220 to 240° F. and including paraffins, olefins, and naphthenes, the catalyst employed being similar to that utilized in the first stage:

Average temperature of reactor _____° F. 1000
Pressure _____ lbs./sq. in. 300
Feed rate
    vols. naphtha/hr./vol. of catalyst 0.25
Hydrogen gas recycle
    cu.ft./bbl. of naphtha 2600
Length of on-stream period _____ hrs. 6

It is to be noted that the severity of the operating conditions maintained in the second stage of the catalytic conversion in the above example was substantially greater than that maintained in the first stage, since both a higher temperature and a lower feed rate or space velocity were employed in the second stage. In general, severity of treatment may be increased by several expedients employed either alone or in conjunction with each other, these being an increase in temperature, a decrease in space velocity, or a substitution of a more active catalyst. In general, I prefer to employ a highly active catalyst in both stages, as exemplified by a catalyst comprising molybdenum oxide supported on activated alumina, and to secure the desired gradation in severity by maintaining a temperature in the second stage at least about 50° F. higher than that employed in the first stage, all other conditions being equal. When the same temperature is employed in both stages, I prefer to employ a space velocity in the first stage at least double that employed in the second stage.

In terms of the resulting products, the operating conditions maintained in catalytic reactor 26 are preferably such that at least 90% of the liquid

product produced consists of aromatic compounds, and preferably are such that the liquid product boiling within the same range as the charge has an aromatic content in excess of about 98%, both percentages being by volume. It will be appreciated that the desired results with respect to the composition of the products produced may be secured with considerable variation in the operating conditions maintained in reactor 26. However, in most instances the invention may be most advantageously practiced by maintenance of the operating conditions in reactor 26 within the ranges tabulated below:

	Operating Condition	Range
Temperature		900-1050° F., and preferably 950-1025° F.
Feed rate, vols. naphtha/hr./vol. of catalyst		0.1-1.0
Added or recycled hydrogen; ratio of mols. of hydrogen charged/mol. of naphtha charged		0.8 mols; and preferably 2-6 mols.
Pressure, any pressure, but preferably		30-450 lbs. gauge.

The conversion products are withdrawn from tower 26 through line 28 and then passed through a heat exchanger, or condenser 29, and then into a high pressure separator 30 maintained at a pressure by means of valve 31 suitable for the separation of normally liquid constituents from the normally gaseous constituents.

The gaseous product withdrawn through valve 31 consists of hydrogen and normally gaseous hydrocarbons. The quantity of hydrogen thus withdrawn is greater than that added through line 27, in other words, catalytic reactor 26 as well as reactor 1 operates with a net production of hydrogen. The hydrogen concentration of the gas withdrawn through valve 31, however, is usually of substantially lower hydrogen concentration than that produced in the first stage. I have ascertained that substantially better results are produced by utilizing the gas of relatively high concentration from the first stage as the hydrogen-containing gas introduced into the second catalytic stage. However, if desired the hydrogen introduced from the first stage may be supplemented by recycling hydrogen withdrawn through valve 31 or may be replaced entirely by hydrogen withdrawn from valve 31. The latter type of operation for example would be preferable in those instances wherein the second stage is practiced as a distinct and separate operation.

In the particular example given above, the liquid product withdrawn through line 32 consisted almost entirely of pure aromatic hydrocarbons as evidenced by its almost complete absorption in Kattwinkel reagent utilized pursuant to the test method referred to in Chemical Abstracts, vol. 22 (1928), 3039. The liquid product had an initial boiling point of 132° F. and end point of 302° F., only 5% of the product boiling below 210° F. Its aromatic content was 99.7% and olefin content 0.3%, both by volume.

The toluene content of the substantially pure aromatic mixture withdrawn through line 32 may be most readily separated by fractional distillation as illustrated, although other methods of isolating the toluene may be employed.

As shown, this mixture is passed by line 34 to a suitable fractionator 35 wherein toluene of sufficient purity to meet "nitration grade," specifications may be separated as a side stream through line 36, and higher boiling constituents such as xylene, and lower boiling constituents such as benzene and the small amount of low boiling ole-

fins, are withdrawn respectively, from the bottom of the reactor through line 37, and overhead through line 38. The overhead fraction is condensed in condenser 49 and may suitably be sent to gasoline storage through line 44 together with the bottoms fraction withdrawn through line 37. Toluene thus separated is usually in sufficient pure condition to be used as a "nitration grade." It may however, if desired, be further purified by hydrofining, further fractional distillation and treatment, or in other suitable manner.

As the catalysts for use in the practice of the invention, I prefer the oxides of molybdenum, chromium, or vanadium, either alone, or in combination, and preferably supported on a suitable carrier, particularly activated alumina. However, the invention may be practiced generally with any dehydrogenating and cyclizing catalyst. For example, oxides or sulfides of the metals included within the lefthand column of Group VI of the periodic table, and other metal compounds, particularly oxides of the metals of the lefthand column of groups IV and V of the periodic table, such as titanium, cerium, thorium, and vanadium. Moreover, while these compounds may be used alone or on various supports or carriers, I regard it highly preferable to utilize them supported on alumina, particularly activated alumina.

While my invention has been described particularly with reference to the production of substantially pure toluene, it is apparent that it may also be applied with suitable modifications to the production of substantially pure benzene, or xylene from hydrocarbon mixtures consisting largely of one of these compounds but, as in the case of the toluene-rich fraction, contaminated with non-aromatic hydrocarbons differing only slightly in their boiling points from the particular aromatic compounds to be isolated. In case benzene is the compound to be isolated, I prefer to employ somewhat more severe operating conditions in the second stage than in the case of toluene-rich fractions, and in the case of xylene somewhat milder conditions, but in either case, the operating conditions are preferably of substantially greater severity than those employed in the first catalytic stage.

It is further apparent, that while the preferred mode for the practice of my invention contemplates a combination of two stages of catalytic conversion the invention is applicable generally to the isolation of toluene, or other aromatic compounds, from hydrocarbon mixtures rich in the desired aromatic compound and contaminated with non-aromatic compounds differing only slightly in boiling range, regardless of the source of such mixtures.

I claim:

1. A method of producing substantially pure toluene which comprises passing a naphtha including a large proportion of non-aromatic hydrocarbons containing from 6 to 12 carbon atoms in the presence of added hydrogen in contact at an elevated temperature with a dehydrogenating and cyclizing catalyst to produce hydrogen and largely convert said non-aromatic compounds to aromatic compounds including a substantial amount of toluene, fractionating the mixture thus produced to separate a toluene-rich fraction including at least 50% toluene together with non-aromatic hydrocarbons containing 6 or more carbon atoms, passing the toluene-rich fraction in contact at an elevated temperature within the range of 950° to 1025° F. with a dehydrogenating and cyclizing catalyst in the presence of added hydrogen and under reaction

conditions of substantially greater severity corresponding to a temperature increase of at least about 50° F. higher than those maintained in the first stage and to an extent such that at least 90% of the normally liquid hydrocarbons thus produced are aromatic, and fractionating substantially pure toluene from the mixture thus produced.

2. A method of producing substantially pure toluene which comprises passing a naphtha including a mixture of aliphatic hydrocarbons containing from 6 to 12 carbon atoms in the presence of added hydrogen in contact at an elevated temperature with a dehydrogenating and cyclizing catalyst to produce hydrogen and largely convert said aliphatic compounds to aromatic compounds including a substantial amount of toluene, fractionating the mixture thus produced to separate a toluene-rich fraction including at least 75% toluene together with non-aromatic hydrocarbons containing 6 or more carbon atoms, passing the toluene-rich fraction in contact at an elevated temperature at least 50° F. higher than the temperature maintained in the initial contacting stage with a dehydrogenating and cyclizing catalyst in the presence of added hydrogen and under reaction conditions of substantially greater severity than those maintained in the first stage and adapted to convert said non-aromatic hydrocarbons to an extent such that at least 90% of the normally liquid hydrocarbons thus produced are aromatic, and fractionating substantially pure toluene from the mixture thus produced.

3. A method of producing substantially pure toluene which comprises passing a naphtha including a mixture of aliphatic hydrocarbons containing from 6 to 12 carbon atoms in the presence of added hydrogen in contact at an elevated temperature with a dehydrogenating and cyclizing catalyst to produce hydrogen and largely convert said aliphatic compounds to aromatic compounds including a substantial amount of toluene, fractionating the mixture thus produced to separate a toluene-rich fraction boiling within the range of about 220 to 240° F. including at least 50% toluene together with non-aromatic hydrocarbons containing 6 or more carbon atoms, passing the toluene-rich fraction in contact at an elevated temperature between 950° and 1025° F. with a dehydrogenating and cyclizing catalyst in the presence of added hydrogen produced in said first stage and under reaction conditions of substantially greater severity than those maintained in the first stage corresponding to a temperature increase of at least 50° F., and fractionating substantially pure toluene from the mixture thus produced.

4. A method for producing substantially pure toluene which comprises passing a naphtha including a large proportion of non-aromatic compounds containing from 6 to 12 carbon atoms in the presence of added hydrogen in contact at an elevated temperature with a dehydrogenating and cyclizing catalyst to produce hydrogen and largely convert said non-aromatic compounds to aromatic compounds including a substantial amount of toluene, fractionating the mixture thus produced to separate a toluene-rich fraction including at least 50 per cent toluene together with non-aromatic hydrocarbons containing 6 or more carbon atoms, passing the toluene-rich fraction in contact at an elevated temperature with a dehydrogenating and cyclizing catalyst in the presence of added hydrogen

and under reaction conditions of substantially greater severity than those maintained in the first stage corresponding to a decrease in space velocity of at least one-half, and fractionating substantially pure toluene from the mixture thus produced.

5. A process for the production of a substantially pure desired aromatic compound which comprises passing a naphtha including a large proportion of non-aromatic compounds containing from 6 to 12 carbon atoms in the presence of added hydrogen in contact at an elevated temperature with a dehydrogenating and cyclizing catalyst to produce hydrogen and largely convert said non-aromatic compounds to aromatic compounds including a substantial amount of the desired aromatic compound, fractionating the mixture thus produced to separate a fraction rich in the desired aromatic compound including at least 50 per cent of the desired aromatic compound together with non-aromatic hydrocarbons containing 10 6 or more carbon atoms, passing the thus separated fraction rich in the desired aromatic compound in contact at an elevated temperature with a dehydrogenating and cyclizing catalyst in the presence of added hydrogen to convert said non-aromatic compounds to aromatic compounds under reaction conditions of substantially greater severity than those maintained in the first stage corresponding to an average temperature increase of at least 50° F., and fractionating the desired aromatic compound substantially pure from the mixture thus produced.

6. The process of claim 5 in which the desired aromatic compound is toluene.

7. The process of claim 5 in which the desired aromatic compound is xylene.

8. The process of claim 5 in which the desired aromatic compound is benzene.

9. A method for producing substantially pure toluene which comprises passing a naphtha including a proportion of non-aromatic compounds containing at least 6 carbon atoms in the presence of added hydrogen in contact at an elevated temperature with an aromatization catalyst to largely convert said non-aromatic compounds to aromatic compounds including a substantial amount of toluene, fractionating the mixture thus produced to separate a toluene-rich fraction including at least 50 per cent toluene together with non-aromatic hydrocarbons containing at least 6 carbon atoms, passing the toluene-rich fraction in contact at an elevated temperature with an aromatization catalyst in the presence of added hydrogen and under reaction conditions of substantially greater severity than those maintained in the first stage corresponding to an average temperature increase of at least 50° F., and fractionating substantially pure toluene from the mixture thus produced.

10. A process for the production of a substantially pure desired aromatic compound which comprises passing a naphtha including a large proportion of non-aromatic compounds containing from 6 to 12 carbon atoms in the presence of added hydrogen in contact at an elevated temperature with a dehydrogenating and cyclizing catalyst to produce hydrogen and largely convert said non-aromatic compounds to aromatic compounds including a substantial amount of the desired aromatic compound, fractionating the mixture thus produced to separate a fraction rich in the desired aromatic compound including at least 50 per cent of the desired aromatic compound together with non-aromatic compounds

containing 6 or more carbon atoms, passing the thus separated fraction rich in the desired aromatic compound in contact at an average temperature at least 50° higher than the average temperature maintained in the first stage with a dehydrogenating and cyclizing catalyst in the presence of added hydrogen, and fractionating the desired aromatic compound substantially pure from the mixture thus produced.

11. A process for the production of a substantially pure desired aromatic compound which comprises passing a naphtha including a large proportion of non-aromatic compounds containing at least 6 carbon atoms in the presence of added hydrogen in contact at an elevated temperature with an aromatization catalyst to largely convert said non-aromatic compounds to aromatic compounds including a substantial amount of the desired aromatic compound, fractionating the mixture thus produced to separate a fraction rich in the desired aromatic compound including at least 50 per cent of the desired aromatic compound and including non-aromatic hydrocarbons containing at least 6 carbon atoms, 15 passing the thus separated fraction rich in the desired aromatic compound in contact at an elevated temperature with an aromatization catalyst and under reaction conditions of substantially greater severity than those maintained in the first stage corresponding to an average temperature increase of at least 50° F., and fractionating the desired aromatic compound substantially pure from the mixture thus produced.

12. In a process for producing substantially pure toluene in which a charging stock consisting essentially of a naphthenic petroleum distillate boiling within the naphtha boiling range is catalytically aromatized by subjection to the action of a dehydrogenation catalyst comprising molybdena and alumina at a temperature between about 875° F. and about 1075° F. in the presence of a carrier gas containing at least a major proportion by volume of hydrogen, at a total pressure of the order of 50 to 450 pounds per square inch at a mol ratio of hydrogen to naphtha charged between about 0.5 and about 8, and at a space velocity of 0.05 to 5.0 volumes of liquid hydrocarbons charged per volume of catalyst space per hour and thereby a resulting product is produced including toluene and some other constituent undesired in the final product and inseparable from said toluene by fractional distillation, the improvement for producing substantially pure toluene which comprises fractionally distilling said resulting product and thereby separating therefrom a narrow cut containing substantially only said toluene in major proportion and constituents inseparable therefrom by fractional distillation and subjecting 20 said narrow cut containing said toluene in the absence of said distillate to the action of a catalyst comprising molybdena and alumina at a temperature between about 900° F. and about 1050° F. in the presence of a carrier gas containing at least a major proportion by volume of hydrogen and a total pressure of the order of from 30 to 450 pounds per square inch and a mol ratio of hydrogen to naphtha charged between about 2 and about 6 at a space velocity 25 of 0.1:1 to 1:1 volume of liquid hydrocarbons charged per volume of catalyst space per hour to transform said cut and render said toluene separable from the transformed product by fractional distillation, the operating conditions in 30 the second stage being maintained such that

11

they correspond to an average temperature increase of at least about 50° F. over those conditions maintained in the first stage, and fractionally distilling to separate substantially pure toluene.

13. The process as defined in claim 12 in which said narrow cut has a boiling range between about 220° F. and about 240° F.

14. The process of claim 12 in which said naphthenic petroleum distillate has an approximate boiling range between about 240° F. and about 418° F.
